Inventor:

Elijah Thorn

UNITED STATES PATENT OFFICE.

ELIJAH THORN, OF SELMA, OHIO.

IMPROVEMENT IN PORTABLE CRABS FOR MOLE-PLOWS.

Specification forming part of Letters Patent No. 25,855, dated October 18, 1859.

To all whom it may concern:

Be it known that I, ELIJAH THORN, of Selma, in the county of Clarke and State of Ohio, have invented certain new and useful Improvements in Modes of Elevating, Moving, and Setting Machines for Operating Mole-Plows; and I do hereby declare the following to be a full, clear, and exact description of the same, reference being had to the accompanying drawings, and to the letters of reference marked thereon.

The nature of my invention consists in elevating and changing the direction of the machine by such devices as will be hereinafter fully set forth.

To enable others skilled in the art to make and use my invention, I will now describe its construction and operation.

In the drawings, Figure 1 is a perspective of the machine complete and ready for use. Fig. 2 is a perspective of the trucks. Fig. 3 represents the boxes, the advantage of which will be more fully seen hereinafter.

In Fig. 1, A represents the frame, which is constructed in a substantial manner.

k k are grabs firmly secured to frame A, with their lower ends inclined to the rear end of the machine, as fully shown in the drawings.

I represents the axle, on which are placed the wheels J J. Said axle is hinged in front to the side of the frame A in such a manner that the axle can roll from under said frame and permit it to rest upon grabs *k k*, as shown in Fig. 1. This is effected by means of two pieces of metal, *b b*, extending up perpendicularly through the axle on each side of the sides of the frame, and a bolt passing from one to the other through said sides.

B represents the tongue, which is secured to axle I.

d d are two braces or supports, which are secured to tongue B and bolted to pieces *b b*.

F represents a frame, in the center of which is located the truck G.

H H are small rollers, which are placed at each end of the cross piece of frame F, as fully shown in Fig. 2.

g g are supports, which are secured to the upper side of frame F, and bolted by means of screws passing through the centers of the rollers. Said screws also afford axles for the rollers *H H*, and are secured by means of nuts, as shown in Fig. 2. On each side of the truck G, and on the under side of the cross-piece of frame F, are two hooks, *h h*, one of which

may be seen in Fig. 1. To these hooks are attached two chains, the opposite ends of which are secured to a cross-piece on frame A, as fully represented in Fig. 1.

a a are two boxes or pieces of metal, which are secured on the inside and at the rear of frame A. The form of said box is shown in Fig. 3. The object of these boxes is to afford a bearing to rollers *H H*, and to enable the direction of the machine to be changed by means of said rollers.

The operation of my machine is as follows: The grabs *k k* being embedded in the earth, and it becoming necessary to remove the machine, the frame F is placed under the rear end, as seen in Fig. 1, the tongue of frame F being in an elevated position and connected with the tongue B by a chain. Power is then applied at tongue B, which simultaneously rolls the axle I under the front end of the machine and pulls the tongue of frame F down, thus elevating the front and rear end of the machine at the same moment, which may then be rolled to any desired locality.

The machine may be easily guided by moving the tongue of frame F to the right or left. My invention is designed to be used in connection with a ditching-plow.

The ordinary reel or capstan is employed in the usual manner.

The frame F answers a double purpose. It not only serves to raise the rear of the machine from the ground after it has been embedded, but it serves to guide the rear of the machine for the purpose of keeping it in line with the plow. It is often very necessary to move the rear of the machine a little to one side or the other, and without this arrangement it would be a very difficult matter to do it without moving and turning the whole machine, which would occupy much time and be a great deal of trouble.

Having thus fully described my invention, what I claim, and desire to secure by Letters Patent, is—

The arrangement of the frame F, as constructed, with the boxes *a a*, which are attached to the rear of the frame A, and with the axle I and wheels J J, the several parts being connected together and used not only for elevating the machine, but for guiding its rear and changing its position, substantially as set forth.

Witnesses:

ELIJAH THORN.
